(57) CLAIM

The ornamental design for a circular magnet for tooth brush holder, as shown and described.

DESCRIPTION

FIG. 1 is a top perspective view of the circular magnet for tooth brush holder showing the new design;

FIG. 2 is a bottom perspective view thereof;

FIG. 3 is a top plan view thereof;

FIG. 4 is a bottom plan view thereof;

FIG. 5 is a side elevation view thereof; and,

FIG. 6 is a perspective view of the circular magnet for tooth brush holder in an example configuration.

The broken lines shown are included for the purpose of illustrating the unclaimed portions of the article and form no part of the claim.
